PRESSBOARD

Henry Sieb, Hammond, Ind.

Application September 1, 1934, Serial No. 742,383

3 Claims. (Cl. 11—1)

In the manufacture of books having stiff, board-like covers, they are placed between press boards having projecting ribs or ledges along the edges and are subjected to heavy pressure, in the process of applying and pasting on the covers; the ribs or ledges of the boards being placed just behind the rear edges of the stiffening boards or cores of the covers, whereby grooves or depressions, forming the hinges for the covers, will be produced. In the old style books the stitches holding the leaves of a book together are at the very back, so that the hinge axes of the leaves are to the rear of the plane containing the hinge axes of the two covers. Therefore, only very narrow hinged grooves or depressions are needed in the covers of the old books, and the ribs or ledges may be simple flat metal strips wider than the thickness of the boards proper arranged on edge and secured to and following along the edges of the press boards.

In the modern type of book in which the leaves are secured together by stitches passing entirely through the body of the book, at some distance from the rear edge and at right angles to the broad faces of the book, the hinges for the leaves and the hinges for the covers are in the same plane and, therefore, the hinge sections of the covers must be made wide. Consequently, the ribs or ledges on the press boards should be made much wider or thicker than for the old style of books. However, when thick metal strips are secured to the edges of the press boards, being held in place by means of many screws, the boards frequently split and become useless. In any event, even in the case of the older, thinner strips, it is not easy to fasten the strips to the boards so that the projection of a strip above and below the broad faces of a board will be equal in extent and be uniform on each face throughout the length of the strip. Because of the trouble encountered in the use of thick strips it is now the custom to employ press boards having only thin edge strips, in applying the covers to the said modern type of book, with the result that the pasting at the hinges is not effectively done and the covers often come loose.

The object of the present invention is to produce a press board provided with pressure ribs or ledges of a novel form which may be of any desired width, be easily applied and which, when applied, will be accurately positioned and will serve to strengthen the board instead of weakening it.

In carrying out my invention, I employ a body member of any usual or suitable construction,

preferably a plywood panel, and set it in a metal frame whose members are channel-shaped in cross section; the marginal portions of the panel fitting into the trough in the frame material, so that the flanges of the frame material overlie and contact with the flat faces of the panel. The flanges of the channel members are made as wide as the depressions to be produced in the book covers and they are as thick as the depth of such depressions. The rib-producing elements, therefore, reinforce and strengthen the wooden panel instead of subjecting it to stresses that tend to split it or break it apart.

In order to reduce the amount of splitting of boards of the old type it has been necessary to make them very thick. Since my improved board is subjected only to compression stresses and not to stresses tending to split it, as is the case with boards to which heavy stresses may be transmitted through the holding screws for the edge strips, it may be made much thinner than the old type of board. For example, whereas a board of the old type would have a thickness of from seven-eighths of an inch to an inch, my improved board need be only, say, half an inch thick. It will thus be evident that in building up a stack of books interspersed with press boards, more books may be placed in a stack adapted to be compressed in a press having an opening of a given height, and more books can be pressed at one time, where my improved boards are used, than is the case where boards made in the old way are employed.

Therefore, viewed in one of its aspects, the present invention may be said to have for its object to produce a novel type of press board which shall make it possible to arrange more books, than heretofore, in a stack of given height composed of books alternating with press boards, and thus permit a larger number of books to be operated upon at one time in a press than could be done by using press boards of the old type.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a plan view of one of my improved press boards; Fig. 2 is an edge view; Fig. 3 is a section, on a much larger scale, through a book and two press boards between which it lies, showing fragments only of the book and board, the

section with respect to the pressboards being on line 3—3 of Fig. 1; Fig. 4 is a view, on a much larger scale, similar to Fig. 1, showing only a corner fragment; Fig. 5 is a view similar to Fig. 4, the metal rim or frame being in section; and Fig. 6 is a section on line 6—6 of Fig. 5.

Referring to the drawing, 1 represents a panel of wood, preferably plywood, there being five plies in the panel illustrated. This panel, which is of any usual or desired length, breadth and thickness, is set into a frame 2 consisting of metal, preferably stainless steel, channel-shaped in cross section; the frame extending along all four edges of the panel and receiving the marginal portions thereof in the channel or trough of the frame. The width of the trough or channel in the frame is, therefore, such that the panel will be a snug fit therein, whereby the flanges 3, 3 of the frame members rest solidly against the broad faces of the panel. By this arrangement, any pressure on the frame at right angles to the plane of the board proper can be transmitted to the panel only as a force tending to produce compression and not as one that places the panel under tension. Consequently, the panel will not crack or be split by the stresses to which it is subjected while in use.

The width of the flanges 3 is equal to the depth of the depressions A to be produced in the cover of the book B, and the thickness of the flanges is equal to the depth of those depressions.

If desired, the several members of the frame may be secured to the panel by a few fastenings as, for example, a few screws 4; the only purpose of the fastenings being to prevent the members of the frame from being sprung in the plane of the board away from the edges. In other words, the screws do not transmit any stresses between the panel and the frame during an operation of book 40 pressing.

The frame may be applied to the wooden panel in any desired way, although I prefer to secure it in such a manner that it may be detached in the event that either the frame or the wooden member is damaged and requires replacement. In the arrangement shown, the frame consists of a single strip of channel section, the flanges of the channel being cut away at the proper points to permit the strip to be bent into a rectangle and bring about miter joints at the four corners. The two ends of the strip meet at some distance from one of the corners, as shown in Figs. 1, 4 and 5. In order to secure the meeting ends of the strip together I place within the channel thereof, across 55 the joint between such meeting ends, a metal block 5. Each strip end is fastened to this block

by a machine screw 6, these screws passing through the web sections of the channels. In order to provide room for the block I cut away a fragment at the corresponding corner of the wooden panel to provide a notch 7 having a length somewhat greater than the block, but preferably of about the same depth as the thickness of the block. The block, as best shown in Figs. 5 and 6, is arranged in this notch in the end of the board. It will thus be seen that the ends of the strip are 10 securely fastened together without relying on the holding effort of screws or the like entered into the wood, so that the integrity of the rim or frame does not depend upon the wooden member of the board. By removing the machine screws 6 and 15 the wood screws 4, the rim or frame may be detached without injury to itself or to the wooden panel.

In using my improved boards they are assembled in the usual way with interposed books in 20 stack formation, the adjacent frame elements above and below each book being set in registration with the through stitching C, as shown in Fig. 3. The stack is then placed under pressure 25 in the usual way.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A press board composed of a wooden panel and a channel-shaped frame surrounding the 35 same, the panel being set at its edges into the channel in the frame.

2. A press board composed of a wooden panel and a channel-shaped frame surrounding the 40 same, the panel being set at its edges into the channel in the frame, the width of the flanges of the frame member being greater than the thickness of the metal in said member.

3. A press board composed of a wooden panel and a channel-shaped frame surrounding the 45 same, the panel being set at its edges into the channel or trough of the frame, said frame being in the form of a strip whose ends meet in a butt joint, a metal block set in the channel or trough of the frame across said joint, and fastenings extending into the block through the web sections of the frame on opposite sides of the joint, said wooden panel having an edge notch in which said block lies.

HENRY SIEB. 55
